of Wisconsin

Application June 24, 1959, Serial No. 56,517

Term of patent 14 years

(Cl. D81—10)

FIG. 1

FIG. 2

FIG. 4

FIG. 3

Figure 1 is a front perspective view of an electric oven showing my new design;

Figure 2 is a rear perspective view thereof taken from the opposite side;

Figure 3 is a side elevational view of one side of the electric oven, its opposite side being of the same appearance; and

Figure 4 is a front perspective view of the oven with the cover therefor shown in opened position.

The dominant features of the design reside in the portions shown in full lines.

I claim:

The ornamental design for an electric oven, substantially as shown and described.
